[57] CLAIM

The ornamental design for a plural leg support for a water tank or similar article, substantially as shown and described.

DESCRIPTION

FIG. 1 is a top perspective view of a plural leg support unit for a water tank or similar article showing my new design;

FIG. 2 is a top elevational view of a tee-type leg bracket showing my new design;

FIG. 3 is a back elevational view of a plural leg support unit for a water tank or similar article showing my new design;

FIG. 4 is a left side elevational view of a plural leg support unit for a water tank or similar article showing my new design; and

FIG. 5 is a bottom elevational view of a plural leg support unit for a water tank or similar article showing my new design.

FIG. 1

FIG. 2
